(57) **CLAIM**

The ornamental design for a wireless charger as shown and
described.

DESCRIPTION

FIG. 1 is a rear elevation view of a wireless charger,
according to a first embodiment of the invention;
FIG. 2 is a front elevation view thereof;
FIG. 3 is top plan view thereof;
FIG. 4 is a bottom plan view thereof;
FIG. 5 is a first side view thereof;
FIG. 6 is a second side view thereof;
FIG. 7 is a first perspective view thereof;
FIG. 8 is a second perspective view thereof;
FIG. 9 is a rear elevation view of a wireless charger,
according to a second embodiment of the invention;
FIG. 10 is a front elevation view thereof;
FIG. 11 is top plan view thereof;
FIG. 12 is a bottom plan view thereof;
FIG. 13 is a first side view thereof;
FIG. 14 is a second side view thereof;
FIG. 15 is a first perspective view thereof; and,
FIG. 16 is a second perspective view thereof.
The features shown in broken lines do not form part of the
claimed design.
The dot-dash broken lines illustrate boundary lines and form
no part of the claimed design.

1 Claim, 10 Drawing Sheets

Related U.S. Application Data

a continuation of application No. 29/748,673, filed on Aug. 31, 2020, now Pat. No. Des. 995,479.
